LINE CLAMP AND MOUNTING TOOL
THEREFOR

Stephen P. Becker, Raymond B. Schoonmaker, and Henry R. Wengen, Poughkeepsie, N. Y., assignors to Fargo Mfg. Company, Inc., Poughkeepsie, N. Y., a corporation of New York

Application November 3, 1949, Serial No. 125,246

3 Claims. (Cl. 81—53)

1

This invention relates to clamps and connectors and more particularly to clamps and connectors for securing wires and cables under difficult operating conditions.

It is an object of this invention to provide a clamp which may be applied to and attached on an electrical line or high tension wire with one hand by a single linesman.

It is a further object of this invention to provide a clamp which will receive tools that make possible the connection between and clamping together of electrical lines easy and requiring a minimum of manipulation.

It is a still further object of this invention to provide a clamp adapted to receive tools for single-handed operation of the clamp and which is also capable of operation in a customary manner.

These and other objects of this invention will become more apparent upon consideration of the following description taken together with the attached drawings in which:

Fig. 1 is a front elevation of a vise type line connector of this invention;

Fig. 2 is an end elevation of the connector in Fig. 1;

Fig. 3 is a plan view of the connector of Fig. 1 engaged in a tool;

Fig. 4 is a side elevation of the tool and connector of Fig. 3, partly in section;

Fig. 5 is a plan view of this invention and a tool;

Fig. 6 is a side elevation of the connector and tool of Fig. 5;

Fig. 7 is an end view of the tool and connector of Fig. 6; and

Fig. 8 is a side elevation of a spacer bar connector of this invention with a wrench partly in section.

In general this invention provides clamps and connectors for use in joining together wires and cables such as are used in telephone communication, on aerial cables, and on high voltage electrical lines where it is important that connectors be applicable to the lines that are connected with a minimum of manipulation and holding of the parts by hand.

In Fig. 1 a vise type connector 10 is shown securing an aerial cable 11 to a messenger cable 12 by means of a lashing wire 13. The lashing wire 13, which is wrapped around both the aerial cable 11 and the messenger cable 12, is clamped in place by the connector 10. The vise type connector 10 is composed of a female element 14 into which a male element 15 fits to provide facing jaws 16 which grip and clamp the messenger

cable 12 and the lashing wire 13. A bolt 17 rests against the element 14 and when turned moves the male element 15 in and out of the female element 14 to open and close the jaws 16. At the top of the element 14 a lug 18 protrudes above a flat surface 19. This lug 18 is shaped so that it has a broad head with a relatively narrow neck portion. Thus positioned on the female element 14, the lug 18 is adapted to be engaged by a suitable slot or recess on a tool which also has means to engage and turn the bolt 17.

One form of such a tool is shown in Fig. 3 in which a wrench 20 having a handle 21 and a slide 22 engages the lug 18 by means of a keyhole slot 23. The handle 21 has a shaft 24 which carries the slide 22. At the end of the shaft 24 a socket 25 is provided and adapted to receive the head of the bolt 17. The shaft 24 is fixed in the handle 21 and is rotatable with relation to the slide 22. Thus, as shown in Fig. 4, with the lug 18 engaged in the slot 23 the shaft 24 and socket 25 may turn while in engagement with the bolt 17 to operate the bolt while the female element 14 is held stationary with relation thereto by the lug 18 in the slot 23 of the slide 22. The rotating bolt 17 draws the male element 15 into the stationary female element 14 to close the jaws 16 and bring about the desired clamping action. As a convenience for obtaining engagement and disengagement of the parts, the slide 22 is mounted on the shaft 24 under the force of an expansion spring 26 which holds it normally in engagement with the handle 21. To engage and disengage the lug 18 in the keyhole slot 23, the slide 22 is urged forward on the shaft 24 to bring the head of the lug 18 in line with the enlarged section of the keyhole slot 23 and in this position the connector 10 may be engaged or disengaged by the slide 22.

A connection with a connector of this invention may be a one-handed operation as demonstrated by the connector 10. In operating connector 10 with a suitable tool such as wrench 20, the connector is inserted in the wrench 20 by urging the slide 22 forward, inserting the lug 18 through the enlarged section of keyhole slot 23 and the bolt head in the socket 25. When released, the spring 26 drives the slide 22 back against the handle 21 and moves the lug 18 into the narrow section of the slot 23. Thus held, the connector 10 can be tightened and loosened by holding the slide 22 stationary with the thumb and forefinger of one hand and rotating the handle 21 and shaft 24 with the remaining fingers and palm of the same hand.

In Fig. 5 another form of this invention is

shown. In this modification a pressure bar type connector 27 is shown held in a tool 28. The connector 27 has two jaws 29 and 30 between which a spacer bar 31 is placed. The jaw 29 is fixed on the base 32 of the connector 27 while the jaw 30 is movably carried in the base 32 on a bolt 33 while the spacer bar 31 slides along the base 32 between the jaws 29 and 30. Thus, wires or cables 35 may be clamped between the jaws 29 and 30 and the spacer bar 31. Grooves 35 are provided on each side of the base 32 for receiving flexible fingers 36 of a clamp carried on a leaf spring 37. The leaf spring 37 is in turn anchored at one end on a strip 38 by a rivet 39. The other end of the leaf spring is formed into a tongue 40 which, protruding through a slot 41, has a head 42 formed at its end so as to prevent the tongue 40 from being withdrawn from the slot 41. A rotatable socket 43 engages the head of the bolt 33 and is attached with the strip 38 in a manner not shown to form the combined tool 28.

The leaf spring 37 carries the connector 27 on the strip 38 with a resilience and freedom of motion that permits the connector to move with respect to the socket 43 and still be held secure and stationary. When the connector is applied to wires or cables, the base 32 is held by the flexible fingers 36 while the socket 43 is rotated to close the jaws 29 and 30 and the spacer bar 31 together until the clamp is tight. Similarly to the described operation of the connector 10, the connector 27 in the tool 28 can be manipulated by hand to open and close. The tool 28 is easily removed from the connector 27 with the socket 43 coming away from the head of the bolt 33 while the fingers 36 slide in the grooves 35.

In Fig. 8 another form of this invention is shown by a spacer-bar connector and a prong and socket wrench. The connector 44 has a body 45 with an integral jaw 46 and a movable jaw 47 sliding in a channel in the body member 45. Between the jaws 46 and 47 a spacer bar 48 slides on outstanding flanges 49 running lengthwise on the body member. A bolt 50 passing through the integral jaw 46 is screw-threaded into the sliding jaw 47 to draw the jaw 47 on rotation of the bolt 50 toward the integral jaw 46 clamping the spacer bar 48 therebetween. Thus wires or cables 51 may be clamped between the jaws 46 and 47 and the spacer bar 48. The bolt 50 has a head 52 with an annular groove 53 around its inside edge.

A wrench 54 in which a socket 55 is carried on a shaft 56 is also provided with a set of flexible prongs 57. The socket 55 receives the head 52 of the bolt 50 while the prongs 57 are extended beyond the socket 55 and are flanged inwardly to project inside the head 52 and engage the annular groove 53. Sliding collar 58 mounted on the shaft 56 encompasses the flexible prongs 57. When the wrench 54 is in release position the collar 58 is drawn back toward the handle of the tool 54 and the prongs 57 spring to a release or open position. When the socket 54 engages the head 52 of the bolt 50 the collar 58 may be moved forward away from the handle to cam the prongs 57 inwardly around the head 52 and into engagement with the annular groove 53. In the closed position the wrench 54 is irreversibly secured to and on the connector 44.

Telephone lines and high tension wires are often supported on high posts and towers. In such a location working on the cables and wires is inconvenient, difficult and dangerous. The lines-

men are greatly assisted by a device which frees a hand or a device which reduces the amount of work that must be done by hand. Among other advantages the linesman, when applying a connector of this invention making a connection, is relieved in the degree of hand manipulation required. Also the connector of this invention may be more satisfactorily and completely tightened. At the same time the connector of this invention can be opened and closed in a customary manner by hand or by a wrench without resort to a tool adapted to permit one-handed operation. Also the connector has a rugged structure and is simple to manufacture.

In the description of the connector of this invention specific embodiments of the invention have been used for the purposes of illustration. These specific embodiments will suggest various adaptations of connectors and clamps to accomplish one-handed opening and closing according to this invention. Thus modifications may be made without departing from the intended scope of the invention as disclosed herein, and for that reason it is not intended that it should be limited other than by the scope of the appended claims.

We claim:

1. In combination a connector adapted to be fastened on a line and having relative moving parts actuated by a threaded screw; and a device for positioning said connector on lines, comprising an elongated support, a socket in the transverse surface of an end of said support, a slideable member on said support, a collar supported on said slideable member, spring prongs mounted on said support lying between said support and said slideable collar and normally biased outward from the center of said support, said spring prongs cooperating with said connector; and transversely extending flanges at the ends of said spring prongs overlapping said transverse surface whereby a longitudinal motion of said collar flexes said spring prongs transversely with relation to said support and moves said flanges in and out over said socket.

2. In combination a connector adapted to be fastened on a line and having relative moving parts actuated by a threaded screw; and a device for positioning said connector on electrical lines, comprising a handle, a shaft mounted on the end of said handle, a head mounted on said shaft, a reduced diameter section of said shaft adjacent said head, a socket in the transverse surface of the end of said head, a collar sliding on said reduced diameter section, a portion of said collar extending axially of said shaft to encompass said head, spring prongs mounted on the outer surface of said head lying between said head and said sliding collar and normally biased outward from the center of said head, said spring prongs and said head cooperating with said connector; and transversely extending flanges at the ends of said prongs overlapping said transverse surface whereby an axial motion of said collar flexes said prongs transversely with relation to said head and moves said flanges in and out over said socket.

3. In combination a connector adapted to be fastened on a line and having relative moving parts actuated by a threaded screw and a device for positioning said connector on lines, comprising an elongated support, a socket in the transverse surface of an end of said support, a slideable member on said support, a collar supported on said slideable member, movable prongs mounted

on said support lying between said support and said slidable collar and normally extending radially outward from the center of said support, said prongs cooperating with said connector; and transversely extending flanges at the ends of said movable prongs overlapping said transverse surface whereby a longitudinal motion of said collar moves said prongs transversely with relation to said support and moves said flanges in and out over said socket.
